CLAIM

The ornamental design for a gaming keyboard for a gaming device, as shown and described.

DESCRIPTION

FIG. 1 is a front left side perspective view of a gaming keyboard for a gaming device showing our new design; FIG. 2 is a top view thereof; FIG. 3 is a bottom view thereof; FIG. 4 is a left side view thereof; FIG. 5 is a right side view thereof; FIG. 6 is a front view thereof; and, FIG. 7 is a rear view thereof.

The shade lines in the figures show contour and not surface ornamentation. The linear shade lines in the figures show a metal surface or a shiny surface.
